Charles H. Wilson

UNITED STATES PATENT OFFICE.

PLATON LAZARIDES, OF NEW YORK, N. Y.

TOOL-HOLDER.

1,252,705.

Specification of Letters Patent.

Patented Jan. 8, 1918.

Application filed March 12, 1917. Serial No. 154,157.

To all whom it may concern:

Be it known that I, PLATON LAZARIDES, residing at New York, in the county and State of New York, have invented certain new and useful Improvements in Tool-Holders, of which the following is a specification.

This invention relates to tool-holders, and more particularly to a combination tool-holder, such that the tool may be set in different positions without disturbing the mounting or adjustment of the holder proper, and whereby various kinds of tools may be held in position to operate upon the work.

The prime object of the present invention is to simplify the construction of tool-holders of this character as hitherto constructed, and to provide an instrument which may be quickly and easily adjusted to various positions.

A further object of the invention is to provide a new and improved instrument of the type which, while possessing all of the advantages of a single tool, may be utilized for the various purposes above indicated, and whereby one using the instrument may use the same to hold a tool to work either as a "left," "center" or "right" tool in a lathe.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, wherein I have illustrated a preferred embodiment of my invention,

Figure 1 is a view in elevation, partly in section, showing the same.

Fig. 2 is a top plan view thereof; and

Fig. 3 is a similar view of the turret head.

Referring now to the drawings, wherein similar reference characters refer to similar

parts through the several views, the reference numeral 1 denotes the shank of the tool-holder, consisting of a straight rectangularly formed bar, which is adapted to be mounted and clamped in the tool supporting device of a lathe in the manner in which an ordinary tool is usually supported. This shank portion at its outer end is provided with an enlarged portion or head 2, having a socket 3, the inner wall 4 thereof being inclined, as clearly shown in Figs. 2 and 3 of the drawings. The reference numeral 5 indicates a turret member, said turret member being of frusto-conical shape, and is adapted to fit nicely within the socket 3, the upper wall 6 of the member 5 engaging with the under surface of the arm 7 of the head 2, and the lateral wall of said turret member engaging with the wall 4 of said head 2, as clearly shown in Figs. 1 and 2 of the drawings.

Turret member 5 is provided with a centrally disposed threaded aperture 8, which is located directly beneath an aperture 9 provided in the arm 7 of the head 2, and extending through the aperture 9 and engaging the threads of the aperture 8 is a clamp bolt 10, having a shoulder 11 adapted to rest upon the outer surface of the arm 7. By means of this construction it will be seen that when the turret member 5 is positioned in the head 2, the same may be firmly clamped against rotative, or in fact any movement therein, by means of this clamp bolt 10.

The turret member 5 is provided with an aperture 12, which extends entirely therethrough, and is so formed as to engage the shank 13 of a tool inserted therein. A threaded aperture 14 is located directly above the aperture 12 and leads into it, said aperture 14 being adapted to receive a clamp screw 15, by means of which the tool 13 is held in position within the aperture 12. The clamp or set screw 15 is provided with a squared or hexagonally formed socket 16 adapted to receive a suitable tool by means of which it may be manipulated.

The turret member 5 is also provided with an aperture 17 extending transversely therethrough, which is adapted to receive the shank or spindle of a boring tool, such as shown at 18, said boring tool being held in position in the aperture 17 as by means of set screws 19 and 20 extending through threaded apertures provided in the upper part of the turret member. The turret member is also provided with another horizontally formed aperture indicated at 21, this aperture being smaller than the aperture 17, adapting it to receive the shank or spindle of a smaller boring instrument, which may be clamped therein as by means of the set screws 22 and 23.

The manner of using my improved tool-holder will be apparent to one skilled in the art without further description, it being observed, however, that when the shank of the tool-holder has been properly supported and clamped in the lathe, a tool of the type required to be used for any particular character of work may be inserted within the aperture 12 and locked therein as by means of the set screw 15. The tool may then be set to the desired position by manipulating the clamp screw 10 to loosen the turret member 5, whereby the latter may be rotated to such position as to carry the tool to the desired position relative to the work, whereupon said turret member may be then clamped firmly in the socket by means of the clamping screw 10. Owing to the fact that the turret member is revolute, it will be seen that tools may be set to work on either the right or left, or in an intermediate position. It will also be seen that when it is desired to use the tool for boring purposes that the required boring instrument can be inserted in either of the apertures 17 or 21.

It will accordingly be seen that I have provided an instrument well adapted to attain, among others, all the aims and objects above set forth, in a very simple and efficient manner.

As many changes could be made in this construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

1. In a tool-holder, in combination, a shank provided with an enlarged head portion, said head portion having its interior wall formed on the arc of a circle and inclined with respect to said shank, a turret member revolubly mounted within said head portion and shaped to closely engage said wall, said turret member being provided

with an inclined aperture adapted to receive the shank of a tool, a set screw adapted to engage said tool to hold the same against movement in said turret member, and a clamp screw extending through said head adapted to clamp said turret member against movement within said head portion.

2. In a tool-holder, in combination, a shank provided with a head portion, said head portion having its interior surface formed upon the arc of a circle and inclined with respect to said shank, a turret member shaped to conform to the interior surface of said head portion, said turret member being provided with an inclined aperture adapted to receive a cutting tool, and with a horizontally disposed aperture adapted to receive a boring instrument, independent means for securing said cutting tool and said boring instrument in position within said turret member, and means for clamping said turret member within said head portion and holding it against movement in any position to which it may be adjusted.

3. In a tool-holder, in combination, a turret member provided with a plurality of intersecting apertures one of said apertures being inclined, and another of said apertures being horizontally disposed, said inclined aperture being adapted to receive a cutting tool, and said horizontally disposed aperture being adapted to receive a boring instrument, independent means for engaging said cutting tool and said boring instrument, and holding them against movement within said turret member, a shank provided with a head portion adapted to receive said turret member, said turret member being adapted to rotate within said head, whereby the tool carried thereby may be moved to any desired position with respect to the work, and means for clamping said turret member against the interior wall of said head portion whereby said turret member is maintained against rotation.

4. In a tool-holder, in combination, a turret member provided with a plurality of intersecting apertures, one of said apertures being inclined with respect to the horizontal adapted to receive a cutting tool, and the others of said apertures being adapted to receive boring tools, independent means for fastening the cutting tool and the boring tools within said turret member, a shank having a head portion adapted to receive said turret member, and a clamp screw extending through said head portion and engaging said turret member, adapted to wedge the latter within said head portion, whereby it is held against rotative movement.

5. In a tool-holder, in combination, a shank provided with a head portion, said head portion being substantially arc-shaped

and having its rear interior wall inclined with respect to the vertical, a turret member revolubly mounted within said head portion, and being shaped to engage with the rear interior wall of said head portion, said turret member being provided with a plurality of apertures adapted to receive tools, and a clamp screw adapted to engage said turret member with the interior wall of said head

portion, whereby rotation of the former is prevented.

In testimony whereof I affix my signature in the presence of two witnesses.

PLATON LAZARIDES.
